FRAMEWORK ARRANGEMENT

Johannes Gillberg, Stockholm, Sweden

Application February 28, 1935, Serial No. 8,700
In Sweden March 7, 1934

2 Claims. (Cl. 20—0.5)

In common frame-works for floors, wherein the flooring is carried by wood-work, such as beams, planks or battens, which are supported by another rigid support, such as concrete, steel girder flanges, masonry or the like, the known and very disagreeable disadvantage occurs that the flooring by and by will sink owing to the drying and shrinkage of the supporting wood-work.

This invention has for its object to reduce to a minimum said disadvantage and this is effected thereby that the wood-work carrying the flooring is supported by the rigid support by means of supporting devices of iron, steel or other suitable material, the lower ends of which rest on the rigid support, whereas their upper ends are secured to the upper edges of the sides of the wood-work carrying the flooring by means of supporting attaching means.

Different embodiments of the invention are illustrated on the accompanying drawing.

Figs. 1 and 2 show supporting devices for wooden beams on top of reinforced concrete. If the two supporting legs 1 are connected by means of a bottom part 2, it will be easy to adjust the girder on the correct level by means of two adjustment wedges 3 before its attachment. Besides the bottom part 2 together with any occurring supporting flanges 4 helps in better anchoring the girder by means of the load of the floor filling 30 thereon.

Figs. 3, 4 and 5 show a supporting device for a wooden girder in the flange of a steel girder. 4 illustrates the foot arrangement for horizontal flange and 5 for inclined flange. The bottom 35 part 2 according to Fig. 1 may of course also be used here.

Figs. 6, 7 and 8 show in different views and in a greater scale details of the attachment of the supporting legs to the sides of the wood-work and their provision, as an alternative, with reinforcement flanges 8. The pressed in supporting tongues 6 are provided for supporting a certain length of the wood-work. Their shape, number and arrangement may vary. The holes 7 are provided for the attaching nails, screws or bolts, which are not needed for carrying the load but help in retaining the supporting devices to the sides of the wood-work.

I claim:

1. Girder arrangement for floors comprising wooden girders directly supporting the flooring, a rigid supporting structure for the floor, supporting members attached at their upper ends to said wooden girders and resting with their base on said rigid supporting structure, attaching means for securing said supporting members to the wooden girders, said attaching means being adapted to carry the load of the flooring and to be secured to the sides of said wooden girders adjacently to the upper edges of the latter for the purpose of reducing to a minimum the settling of the floor due to shrinkage of the wooden girders.

2. Girder arrangement for floors as claimed in claim 1, and wherein such supporting members are arranged in pairs on opposite sides of the wooden girder, the bases of said pairs of connecting members being interconnected by means of a base plate adapted to rest upon the rigid supporting structure.

JOHANNES GILLBERG. 35
